Filed July 14, 1967, Ser. No. 7,805

Term of patent 14 years

(Cl. D48—16)

FIG. 3

FIG. 1 is a perspective bottom view of the luminaire lens according to the present invention;

FIG. 2 is a perspective top view of the luminaire lens according to my new design;

FIG. 3 is a top plan view of the luminaire lens according to FIG. 1;

FIG. 4 is a bottom plan view of the luminaire lens according to FIG. 1;

FIG. 5 is a side view of the luminaire of FIGS. 1 to 4 as seen in the direction of the arrows 5-5 shown in FIG. 2; and

FIG. 6 is a section taken along the line 6-6 of FIGS. 1 to 4.

The central portion of the lens has been shown broken away and in broken lines in FIGS. 3, 4, 5, and 6, for convenience of illustration. The pattern is understood to be continuous throughout the lens.

I claim:

The ornamental design for a luminaire lens, substantially as shown and described.
